UNITED STATES PATENT OFFICE.

RAY G. COATES, OF PASADENA, CALIFORNIA, ASSIGNOR TO VALLEY MOULD AND IRON CORPORATION, OF SHARPSVILLE, PENNSYLVANIA, A CORPORATION OF NEW YORK.

REMOVABLE-SIDED INGOT-MOLD.

1,813,259.

Specification of Letters Patent. Patented Aug. 19, 1919.

Application filed October 21, 1918. Serial No. 259,082.

To all whom it may concern:

Be it known that I, RAY G. COATES, a citizen of the United States, and a resident of the city of Pasadena, in the county of Los Angeles, State of California, have invented new and useful Improvements in Removable-Sided Ingot-Molds, of which the following is a specification.

This invention relates broadly to metallurgy and more particularly to an ingot mold.

The principal object of the present invention is an ingot mold provided with removable portions and so constructed that the parts may be standardized in such manner that corresponding parts of different molds are interchangeable, whereby economy in manufacture and labor is facilitated.

A further and equally important object of the present invention is an ingot mold of the character specified, wherein the sides of the ingot preferably are without draft whereby the ingot may be more readily treated by rolling or forging than if the sides were tapered or inclined, and wherein one end of the ingot is adapted to be at substantially right angles to the axis of the ingot so that the said ingot may be set in an upright position in a soaking pit.

A still further object of the present invention is an ingot mold of the character specified wherein the mold is constructed in such manner as to facilitate the casting of ingots several sizes smaller than the maximum size for which the mold is designed and also wherein the top of the mold is without obstructions so that no part of the mold will interfere with any desired apparatus for keeping the top of the ingot fluid while other portions are crystallizing.

A still further object of the present invention is an ingot mold of the character specified and being provided with hinged side members secured to a body member by means of pintles which extend through oval shaped openings in such manner that the pivots for the said hinged sides do not interfere with the clamping means for locking the sides in position against the body portion.

A still further and primary object of the present invention is a cast ingot of steel or the like being substantially rectangular in cross-section and having one end arranged

at substantially right angles to the axis of the ingot.

The present invention possesses many other and advantageous features some of which together with the foregoing will be set out more at length in the following description wherein will be outlined in full that form of the invention which I have selected for illustration in the drawings accompanying and forming a part of the present specification.

In the drawings and specification I have disclosed only the preferred form of my generic invention, but it is to be understood that I do not limit myself to such form because my invention may be embodied in a multiplicity of forms each being a species of my invention, it being understood that by the claims succeeding the description of my invention I desire to cover the invention in whatsoever form it may be embodied and practised.

In the drawings like characters are used to represent like parts throughout the several figures thereof.

Figure 1 is an elevational view of a preferred form of my ingot mold.

Fig. 2 is a plan view of the device shown in Fig. 1.

Fig. 3 is an end view of the device shown in Fig. 1.

Fig. 4 is a detail view taken on line A—A, Fig. 2, looking in the direction of the arrows.

Fig. 5 is a perspective view illustrating an ingot comprising a feature of my invention.

Heretofore in the steel art it has been customary to form steel ingots from which rolled or forged steel articles are manufactured, and it has been the practice to cast these steel ingots in tapered vertical molds. These molds have been made of iron alloys and constructed of such thickness as to chill the ingot and since the chilling progresses from the walls of the mold inward, the ingot often has defects in the center thereof which are known in the art as "pipes". In order to facilitate the removal of the ingot from the mold the sides of the mold are tapered and the resultant ingot necessarily is tapered. The tapering of the ingot interferes to a certain extent with the rolling operation, in that the rolls must be first set

to accommodate the larger portion of the ingot and then gradually closed to roll the smaller portion of the ingot. By this operation it is obvious the larger portion of the 5 ingot undergoes more rolling than does the smaller portion, consequently the texture of the resultant product is not entirely uniform. Because of roughness on the interior of the mold and for other reasons it is 10 not uncommon for the ingot to stick in the mold, and the molds are usually subjected to severe treatment in order to loosen the ingot. Because of this rough treatment the life of ingot molds is relatively short and 15 the problem of furnishing adequate ingot molds becomes an item of considerable expense in the steel industry.

The present invention overcomes the difficulties of the known art by providing an 20 ingot mold which produces a straight sided ingot of substantially rectangular cross-section and wherein the ingot is released from the mold by loosening or removing the sides of the mold. This action obviates 25 sticking of the ingots in the mold and obviates the necessary rough treatment for removing the ingot. Furthermore, because of the fact that the mold comprising the present invention is made up of inter- 30 changeable parts, if any portion of the mold is injured it is not necessary to destroy the entire mold since the injured part may be removed. Also since the ingot is cast on one side instead of one end the formation of 35 "pipes" and defects is eliminated.

The preferred form of the mold consists of a body 1 having integral ends but open at the sides, which latter are adapted to be closed by side members 2 hinged to the body 40 member. The body carries lugs 4 at one end and the side members are provided with co-acting lugs 5. Holes 6 are cast in these lugs and rods 7, acting as pintles, are inserted in the holes. The combination forms a 45 hinge for each side and allows the side members to be swung laterally so as to free the ingot and allow the ingot tongs to take hold of the ingot. The body is provided with cast in staples 8 and the side members are 50 cast with holes 9 so that when the side members are swung against the seats on the body the holes 9 will pass over the staples 8. Wedges 11 can then be driven under the staples so as to wedge the side members to 55 the body. In order that the side members may come to a free contact with the body the holes 6 through which the pintles 7 pass, in the lugs on the side members, are cast oval in horizontal section and with their long 60 diameter normal to the plane of the side member. This allows lost motion to the hinge in a direction normal to the plane of the side member, and also permits the side member to fit snugly against the body with- 65 out any strain on the hinge. The oval shape

to the holes 6 allows no lost motion in the direction of the plane of the side members, consequently the pintles sustain and guide the side members so that they readily pass over the staples and do not strike on them. 70 When both side members are closed and the wedges 11 are driven under the staples the wedge 12 may be inserted and driven between the locking arms 14 and 15 at the right end of the mold, thereby tightening the 75 ends of the side members in one operation. The above mentioned lost motion in the hinge allows this action. Wedge 12 should not be tightened until the staple wedges 11 are driven up in order that the joint at the 80 bottom may be tight and secure. The joint between the sides and the body when desired or necessary may be made tight by a clay, or other, luting.

In opening the mold the staple wedges 11 85 are driven out and the sides swung open and the wedge 12 is loosened when the sides swing out angularly. From this it will be clear that the action of the wedge 12 is to swing the side members on the pintles; therefore it should not be driven up until after 90 all of the staple wedges 11 are driven in. It will be noticed that all of the side wedges are arranged to be driven horizontally. The reason for this is that when the parts are 95 hot it is not desirable to handle them. In the arrangement shown these wedges may be knocked out by a blow of a sledge and yet at the same time there is no tendency of these wedges to fall out. From the preceding it will be observed that by knocking 100 out a few wedges and swinging the side members a foot or so the ingot tongs may readily grip the sides of the ingot and lift it from the mold.

In the vertical molds a small variation in the depth of the metal poured into the mold does not make much difference in the weight of the ingot, but in a horizontal mold the horizontal section of the metal is so much larger that a small variation makes quite a large difference in the weight of the ingot. The notch 16 at the left of the body is an overflow warning. It is made deep enough to overflow for the minimum size of ingot desired from the particular size of the mold. The notch 16 may be dammed as desired, with loam or clay so as to overflow any desired intermediate size of ingot between the minimum and maximum sizes. It is somewhat difficult to judge the depth of hot metal in a mold. In using my mold, the metal can be rapidly and safely poured into the mold and promptly shut off when the first signs of an overflow appear at the notch, and an 115 ingot of predetermined weight is thus obtained. The very small "tail" of metal that cools in the notch and is attached to the ingot does not interfere with the rolling 120 since it is at the extreme end of the ingot. 130

From Fig. 1 it will be noted that the right interior end 17 of the mold is square with the inner bottom surface while the left end 18 has considerable draft. If the left 5 end of the ingot is raised by the ingot tongs gripping the ingot on its sides the draft shown on the left will allow the ingot to "up end" freely, and it will stand upright on its square right hand end when placed 10 in the soaking pit. The side may or may not be given draft for when the sides are open all side contact with the ingot is removed, but as stated the sides preferably are straight to provide an ingot of rectangular 15 cross section.

Since the sides and the body are made to a standard the breaking or damage of a part of the whole mold will require the replacement of only that part. A new side 20 or sides; a new body member on old sides; or the assembly of two old but good sides with an old but good body, are all practicable procedures. This feature will allow a long life to the mold. Furthermore since 25 the strains of stripping are removed by not moving the ingot parallel to any draft surface there is little damage to the parts in the stripping operation. This fact coupled with that of the renewal of the parts will 30 give a very greatly increased life to a given amount of metal cast into these molds over the same amount cast into molds of the vertical pattern.

The "gravity contact" area between the 35 ingot and the mold is one long side instead of merely an end, as in the vertical mold, and therefore is much greater than where the only "gravity contact" is one end of the ingot as where the ingot is cast in a vertical 40 mold as is common in the art.

In Fig. 5 is shown an ingot in accordance with my invention wherein the sides 19 and 20 are substantially parallel, with the end 21 inclined and the end 22 at right angles 45 to the axis of the ingot. The top side 23 of the ingot has been out of contact with the chill mold and therefore is the only rough side of the ingot. This side is very easily treated or removed in the final treatment 50 of the ingot. In view of the relatively large horizontal area of the ingot as compared to the vertical dimension there is more and better opportunity of the gases, freed during cooling of the metal, to escape. 55 As pointed out the inclined end 21 on the ingot facilitates removal from the mold and the squared end 22 enables the operator to stand the ingot upright in a soaking pit.

I claim:

60 1. An ingot mold comprising in combination a base having end portions integral therewith and with the mold face of one of said end portions at substantially right angles to the mold face of the base and with 65 the mold face of the other end inclined up-

wardly and outwardly relatively to the mold face of said base to provide draft, side members hinged to said base and provided with openings adjacent the body portion of said base, staples anchored in said body portion of the base and extending through the openings in the side members, wedges adapted to be driven through said staples to clamp said side members to said base, arms provided on said side members 70 and overlapping adjacent one end of the base, and means coöperating with said arms to clamp the ends of said side members against the said base.

2. A mold for steel ingots and the like 80 comprising in combination a body member being formed with integral ends and base portions, said body member having substantially flat sides, staples anchored in the body member adjacent the said sides and 85 extending outwardly therefrom, side members hinged to said body members and adapted to form contact with the sides thereof, said side members being provided with openings through which the staples 90 are adapted to extend, each side member being provided with an arm adapted to extend across a portion of one end of the body member and to overlap the arm on the opposite side member, wedges adapted to 95 extend horizontally through said staples, and a wedge adapted to extend between the arms on the side members in such manner that when the wedges are driven the side members are tightly clamped against the 100 sides of the body portion.

3. In an ingot mold and the like the combination of a body portion comprising substantially a U-shaped member with one end inclined and the other end substantially vertical, a pair of side members adapted to co-operate with said body portion to form an open box in which the ingot is adapted to be cast, said side members being pivoted to said body portion by loosely supported 105 pivot hinges, and means comprising horizontal wedge members adapted to clamp said sides against the said body portion.

4. An ingot mold for steel ingots and the like comprising in combination an open-sided U-shaped body portion, a pair of side members adapted to coöperate with said body portion to form an open box in which said ingot is to be cast, hinges securing said sides to said body portion, said hinges being provided with oval shaped openings for the pintles in such manner as to enable the hinges to guide the said sides without interfering with the contact between the sides and the body portion, and horizontal wedge-shaped members for clamping said sides against the said body portion.

5. A mold for steel ingots and the like comprising in combination an open sided body portion being provided on one end 130

- with hinge lugs, a pair of side members adapted to coöperate with said body portion to provide an elongated open box forming a mold for said ingot or the like, lugs 5 integral with said side members and overlapping the lugs on the body portion to form leaves of hinge members, certain of said lugs being provided with oval-shaped openings the major axis of which is substantially normal to the plane of the mold 10 faces of said sides, pintles extending through said openings and forming pivot members for the hinges, and means for clamping said sides against said body portion, the parts being constructed and arranged in such manner that the pintles of the hinges act to guide the said sides without interfering with the contact of said sides against the body portion when the sides are 15 under the influence of the clamping means.
6. An ingot mold for steel ingots and the like comprising the combination of a body member having integral base and end portions and comprising an open-sided member, anchoring means carried by said base portion and by one of said end portions, side members adapted to close the open 20 sides of said body member and form an open box in which the steel ingot is adapted to be cast, wedges constructed to coöperate with said anchoring members and said side members to secure the parts together, and loosely constructed hinges operatively connecting said side members to said body 25 portion.
7. An ingot mold or the like comprising in combination an open sided body member, detachable side portions constructed to coöperate with said body portion to form an 30 open box comprising said mold, anchoring means carried by said body member and extending outwardly beyond the exterior surfaces of the side members, and wedges coöoperating with said anchoring members 35 and said side members to lock the parts together to complete the said mold.
8. An ingot mold or the like comprising in combination a body portion having a horizontally extending base, ends extending 40 upwardly from said base, outstanding anchoring members anchored in said base and in one of said ends, side members hinged to said body portion, and means adapted to coöperate with said anchoring 45 members to lock said side members against said body portion.
9. An ingot mold or the like comprising in combination a body portion, side members hinged to said body portion, arms provided on said side members and adapted 50 to overlap, a wedge adapted to be driven 55

between said overlapping arms and tending to swing said sides on the said hinges.

10. An ingot mold for steel ingots and the like comprising a body portion, a plurality of staples carried by said body portion, lugs adjacent one end of body portion and adapted to comprise leaves of a hinged member, side pieces substantially flush with top of said body portion, said side members being provided with lugs constructed to coöperate with the lugs on the body to form hinges, pintles extending through said lugs and loosely connected therewith, and wedging devices for securing said side pieces to 75 said body portion.

11. An ingot mold for steel ingots and the like comprising in combination a body portion, side members for closing the sides of said body portion, portions of said side members overlapping said body portion, and a wedge adapted to be driven between said overlapping portions to draw said side members tightly against said body portion.

12. An ingot mold for steel ingots and the like comprising a horizontal mold for ingots, the sides of said mold being movable and extending substantially vertical, a body portion having one end substantially vertical and the other end inclined outwardly and upwardly, means to lock the sides against the body portion, and one end of said mold being provided with an overflow opening, substantially as specified.

13. As an article of manufacture an ingot mold comprising a body portion, side members hinged to the body portion, the said hinges being provided with oval-shaped openings the major axis of which is substantially normal to the mold face on the 95 side members, and means for locking said side members to said body portion.

14. As an article of manufacture an ingot mold comprising a body portion, a pair of vertical sides hinged at one end to said body portion, one end of said body portion being provided with an overflow opening, and the other end of said body portion being substantially vertical, substantially as specified.

15. As an article of manufacture, an ingot mold comprising a body portion, anchoring members carried by said body portion, removable sides adapted to coöperate with said body portion and being provided with openings for the passage of the anchoring members, and horizontal wedges adapted to be driven in said staples and against said side members to lock said side members to said body portion.

RAY G. COATES.
